THEODORE F. ROCKWELL, OF YORKVILLE, NEW YORK.

Letters Patent No. 77,218, dated April 28, 1868; antedated April 15, 1868.

IMPROVED BLIND-SLAT FASTENING.

The Schedule referred to in these Letters Patent and making part of the same,

TO ALL WHOM IT MAY CONCERN:

Be it known that I, THEODORE F. ROCKWELL, of Yorkville, in the county, and State of New York, have invented a new and improved Fastening for Blind-Slats; and I do hereby declare that the following is a full and exact description thereof, which will enable others skilled in the art to make and use the same, reference being had to the accompanying drawings, and to the letters of reference marked thereon.

This invention relates to a new and improved device for securing the slats of blinds in a fully open and closed state, and at any point between these two positions. The slats of blinds soon shrink after being made and exposed to the air and sun, and become so loose that they cannot be retained at any desired point without some kind of fastening.

Various devices for this purpose have been patented, but so far as I am aware there are none in very general use, some being too expensive, and others liable to get out of repair, and not capable of being manipulated with facility.

The object of the present invention is to obtain, for the purpose specified, a simple, economical, and easily-adjustable device, as hereinafter fully shown and described.

In the accompanying sheet of drawings—

Figure 1 is an inner side view of a window-blind provided with my invention.

Figure 2, an edge view of the same.

Figure 3, a lower end view of the same.

Figure 4, an enlarged detached view of a bent wire or rod pertaining to the same.

Similar letters of reference indicate like parts.

A represents the slats of an ordinary window-blind, and B the rod to which the slats are connected. These parts being of usual construction do not require a special description.

To the lower end of the slat-rod B there is secured, by a pivot, a, a pendent plate, C, which is perforated with a series of holes, b, one above the other, and which also has a slot, c, in it, extending nearly its whole length, as shown clearly in fig. 2.

This plate C passes loosely through a socket or guide, D, secured to the bottom rail d of the blind. This socket or guide may be constructed of a piece of sheet metal, bent in the form as shown clearly in fig. 3, and to the socket or guide D there is secured a lateral guide, E, in which a bent wire, F, is fitted, and allowed to slide freely. The wire, F, is bent or doubled, so as to form an eye or loop, e, at one end, and have two parallel parts, f g, the former, f, being perfectly straight throughout its entire length, and the other, g, having a hook, g', at its end, as shown in fig. 4.

The part g passes through the slot c of C, and through holes in the socket or guide D, the hook g' of g preventing the wire from drawing out from the plate C, and the socket or guide D. The other part, f, of the wire, F, passes through holes in the socket or guide, and through any one of the holes b in plate C.

From the above description it will be seen that by pulling or drawing the wire, F, in the direction indicated by arrow 1, fig. 3, the part f of the wire will be drawn out of the hole b in the plate C, and the slat-rod B raised or lowered, and the slats A turned or adjusted as desired, the rod B, and consequently the slats, being retained or held by passing the part f of the wire, F, through the hole b in C, which is opposite or in line with f.

By this simple device the slats may be held or retained in an open or closed state, or at any point between these two positions, and by a very simple adjustment.

Having thus described my invention, I claim as new, and desire to secure by Letters Patent—

The pendent plate C, attached to the slat-rod B, and perforated with holes b, and an oblong slot c, in combination with the bent wire or rod F, and the socket or guide D, all constructed, arranged, and applied to the window-blind, to operate substantially in the manner as and for the purpose set forth.

The above specification of my invention signed by me, this 25th day of July, 1867.

THEODORE F. ROCKWELL.
